TO ANTHONY J. WISSEL AND MAX S. WISE, BOTH OF CINCINNATI, OHIO, PARTNERS
DOING BUSINESS AS AUTO SALES AND SERVICE COMPANY.

LIGHTING SYSTEM FOR AUTOMOBILES.

1,421,549.

Specification of Letters Patent. Patented July 4, 1922.

Application filed August 15, 1917. Serial No. 186,315.

To all whom it may concern:

Be it known that I, WILLIAM FRANKLIN PENROD, a citizen of the United States, residing at Blanchester, in the county of Warren and State of Ohio, have invented new and useful Improvements in Lighting Systems for Automobiles, of which the following is a specification.

My invention relates to light controlling devices for automobiles having a plurality of lamps supplied from a source of varying current voltage dependent on the motor speed, such for example as a motor-driven generator with permanent field magnets, by 10 means of which, at the desire of the operator, the electric current employed in lighting both lamps, may be wholly or partly directed through one in order to temporarily gain a greater illumination thereby while 15 still maintaining if desired some efficiency in the other light. Many laws require that both lights shall be kept lighted at all times and this invention complies with such laws while providing the increased illumination 20 at times desired.

In the system at present used, to provide increased illumination, a special hand switch is employed to cut out one lamp and allow the entire current to pass through the 25 other. Such increased illumination is needed, as a rule, only in conditions of possible danger when motor speed is much lowered and the current is reduced, causing a corresponding reduction in the illumination in 30 both lamps. With these present devices, it sometimes happens that when motor speed is increased, the car operator neglects through inadvertence or pre-occupation to release the cut out switch and the excess of 35 current through one lamp is allowed to continue until the lamp is burnt out.

My invention, which is applicable to the very large class of automobiles in which the gear-change control is effected by the foot, 40 provides a control of the light by the same foot; and is so constructed and arranged as that the operation of the light-control is alternative with that of the gear-control and is maintained only by continued 45 foot-pressure and is self-releasing when such pressure is discontinued.

The cut-out of the second lamp—which may be partial or total—is therefore made temporary; and is maintained by the direct

and continuing act of the operator; and the 55 release of the same (when a change of gear is desired) becomes automatic and instinctive and is, so to speak, absorbed in the act of changing the gears and is therefore not subject to neglect or forgetfulness of the operator; and the hands of the operator are left 60 entirely free.

My invention is illustrated in the accompanying drawings in which Figure 1 is a diagrammatic representation of the lamps 65 and feed circuits with the additional ground connection embodying my invention; and Figure 2 is a diagrammatic view of the gear-shifting pedals and the additional ground circuit, with the relative positions of the 70 foot shown in dotted line.

Referring now to the drawings, A¹ A² designate the lamps of an automobile connected across the body of the car by the electric conductor a¹ and from the second lamp 75 a² by electric conductor a² to a ground g¹ usually on the radiator. The supply of current is from the magneto M to ignition, to the horn and to the lamps A¹ A² by conductor a³ having a cut off switch S¹ at the lamp side. 80 (The electric connections to ignition and to the horn, being no part of this invention, are not shown in the drawing.)

At present, in order to cut out one of the lamps and pass the entire lamp-current 85 through the other, an ordinary hand switch is employed or an automatic switch involving a costly multiplicity of mechanism, "choke coils," etc., which, moreover, is not satisfactory because neither quick enough 90 nor positive enough in action. The hand switch is also objectionable and disadvantageous because it takes one hand to operate it and release it and thus requires attention and the service of a hand which may be 95 needed for other purposes. If this switch be closed it must in order to avoid burning out the lamp, be released before throwing the car into neutral or low gear, and therefore requires continuing and special attention, which, in the multiplicity of other 100 cares, is often neglected and damage ensues.

My invention consists in giving to the foot that operates the gear-control, control also, of an independent ground circuit from 105 a connection between the lamps through the medium of an automatically-opening switch located in immediate proximity to the gear-

control. This is best carried out by supplying an alternative electric conductor a^4 connecting with the conductor a^1 between the lamps and to a ground g^2 with an electric 5 resistance C, introduced somewhere between where a^4 connects to a^1 and where a^4 connects to g^2 . A suitable resistance may be obtained by the use of a small electric lamp which could be used for other purposes such 10 as a dash light or tail light. At some convenient point on the electric conductor a^4 , I place a foot switch S^2 standing normally open and held closed only by continued pressure of the foot. It is preferably an arm of 15 elastic metal adapted to be deflected by a push-button S^2 to make contact but normally springing back out of contact by its own resiliency when released, and preferably located upon such a convenient part of the 20 frame as is most readily accessible to the operator's foot with which he changes the gears, adjacent to the gear lever. A cut out electric connection a^5 and a switch S^6 provide means for avoiding the effect of the 25 resistance C if at any time the current is so weak, its full intensity is of necessity to be concentrated in the lamp A¹.

The relative positions of parts as shown in Figure 2, in which the foot lever L (for low 30 speed and clutch); R (for reverse); and B (for brake), are shown side by side, and adjacent to lever L at the left is shown the light control (push button) S^2 . The normal positions of the operator's feet F¹ and F² are, in 35 relation to the other elements, shown in dotted outline, the left foot being relatively situated between the biased open switch S^2 of the auxiliary light control circuit, at one side, and the low-speed gear-control L, at its 40 other side, both operated by the same foot, compels a limitation of use of the foot at one or the other side alternately.

Thus the switch S^2 is operated with the same foot by which the car is thrown into 45 low or neutral and, therefore, the switch must necessarily be released before this can be done. The act of releasing is, as it were, instinctive because it is part of the act of operating the gears because the foot must 50 be raised from the lamp cut-out switch S^2 in order to place it on the gear-lever and thus prevention of burning out a lamp is definitely assured. Even where the law does not 55 require both lights to be kept lighted it is generally conceded to be desirable to do so because persons coming from the opposite direction can better judge the width of the machine and, therefore, avoid collision. By 60 the use of my invention, the operator has practically all the advantage of the old types of illumination increasing devices while pro-

viding the security that careful operators require and affording protection for the lamp into which the light is concentrated. The mechanism employed is quite inexpensive, is positive in its results and as it involves no complicated parts, does not readily get out of order or wear out by use.

I claim as my invention and desire to secure by Letters Patent of the United States:

1. In an electric light system for automobiles having a plurality of lamps in series, a source of current supply with voltage dependent on the speed of the motor; a gear control of motor speed operated by a foot 75 pedal biased to the position of low generator voltage; an independent ground connection leading outward from the lamp circuit between the first and subsequent lamp or lamps; and a switch in said ground connection biased to normally open position and an operative foot pedal adjacent to the gear control pedal in such relation that both 80 pedals are operated by the same foot alternately.

2. In an automobile electric lighting system having a plurality of lamps in series; a source of current supply of varying voltage dependent on motor speed, a normally open auxiliary ground connection leading out of 90 the lamp circuit between the first and subsequent lamps; a closing switch in said auxiliary ground connection; biased to open position; a foot pedal for temporarily closing said switch by foot pressure; change 95 gears and a foot pedal for shifting said gears, biased to the position in which the generator voltage is low, said foot pedals being located side by side in such position and space relation as necessary to be operated by the same foot in alternation.

3. In an electric lighting system for automobiles, the combination with a variable potential generator, a headlight lamp; an electric circuit connecting said generator 105 and said lamp; voltage reducing means in said circuit for reducing the voltage supplied to said lamp; and a gear control pedal biased to high gear position; of control means for rendering said voltage reducing 110 means ineffective; said control means being biased to inoperative position and situated adjacent to said gear pedal, and being operable alternately with said pedal by the same foot.

In testimony whereof I have hereunto set my hand in presence of two subscribing witnesses.

W. FRANKLIN PENROD.
